UNITED STATES PATENT OFFICE.

ADOLPH ROSNER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

INTERNAL-COMBUSTION ENGINE.

1,208,377.

Specification of Letters Patent. Patented Dec. 12, 1916.

Application filed September 28, 1911. Serial No. 651,690.

To all whom it may concern:

Be it known that I, ADOLPH ROSNER, a subject of the Emperor of Austria-Hungary, and a resident of Bridgeport, in the county of Fairfield and State of Connecticut, have invented an Improvement in Internal-Combustion Engines, of which the following description, in connection with the accompanying drawings, is a specification, like characters on the drawings representing like parts:

This invention relates to internal combustion engines and particularly to the means for controlling the admission of fuel to the cylinder and the exhaust of the waste gases therefrom.

In carrying out my invention I preferably make use of slide valves. The valves as herein disclosed, however, are so designed and disposed that an extremely high degree of compression can be readily attained while, at the same time, the valves are simple in construction and operation and are free from the difficulties of lubrication, overheating and other troubles to which valves of this class have heretofore been subjected.

The invention will be best understood by reference to the following description when taken in connection with the accompanying illustration of one specific embodiment thereof, while its scope will be more particularly pointed out in the appended claims.

Figure 1 is a transverse sectional elevation taken through a cylinder of an engine equipped with one form of my invention; Fig. 2 shows in perspective the connection of the actuating devices to one of the valves; Fig. 3 is a sectional elevation in detail taken on the line 3-3, in Fig. 1; Fig. 4 shows a modified form of the engine illustrated in Fig. 1; and, Figs. 5, 6, 7 and 8 are sectional elevations, partly diagrammatic, showing the piston and valves in different positions.

Referring to the drawings, and particularly to the embodiment of the invention there shown, the engine there illustrated is provided with a fixed main cylinder 1, supported upon the crank casing 2. The piston 3 is provided, connected by the rod 4 to the crank 5 and crank shaft 6. The working space of the cylinder, or that through which the piston travels, is surrounded by the water jacket 7 and the piston slides in direct contact with the water jacketed walls

of the fixed cylinder. The rear end of the cylinder is closed by the cylinder head 8, which is bolted or otherwise fixedly secured to the top end of the cylinder, forming preferably a gas tight joint and a gas tight closure for the end of the cylinder. The cylinder head has the portion 9 which projects into the rear end of the cylinder, the projecting portion being of lesser diameter than the diameter of the cylinder providing thereat an annular space 10 between the cylinder 65 and the reentrant walls of the head. The cylinder head has the centrally arranged spark plug 11 and is provided also with the water jacket 12.

At the rear of the cylinder, beyond the working space thereof and in close approximation to the projecting portion of the cylinder head, are provided the oppositely disposed admission and exhaust ports 13 and 14, respectively. While these ports might be otherwise located, they are preferably formed directly in the walls of the cylinder bore itself and as indicated in dotted lines extend each part way around the cylinder.

In the described embodiment of the invention the ports 13 and 14 are controlled by independently movable slide valves 15 and 16, respectively. While the valves might consist of flat plates or have other than a curvilinear shape, for convenience in construction as well as efficient operation each valve preferably comprises an arc-shaped but non-cylindrical segmental plate, having a curvature corresponding to the curvature of the cylinder bore, so that it is adapted to seat thereagainst. These valve plates or slides are moved independently up and down by means to be fully described so that their ends which in their lowermost positions terminate short of the piston and the working space of the cylinder, are alternately projected each over its respective port to close the same and withdrawn therefrom to open the port. The valve sides at their inner faces are exposed to the pressure of the gas contained in the cylinder so that they are automatically seated during the compression and working strokes of the piston, the high pressure exerted radially outward against the valves, holding them effectively each against its seat, preventing all leakage at the ports.

To move the valves independently and in properly timed relation actuating devices are

provided, having connection with the valves through openings 17 and 18 formed in the cylinder walls and in the seat over which the valves slide. In the openings 17 and 18 there are pivoted the actuating levers 19 and 20, respectively, shown in perspective in Fig. 2. These are connected to the valves at their outer sides or faces, each by means of a trunnion block 21, seated between lugs 22 projecting outwardly from the valves, the block being spanned by and jointed to the forked ends of the lever.

The openings 17 and 18 being formed in the cylinder and the valves being pressed automatically thereagainst by the pressure within the cylinder space, all leakage is prevented through the openings in the same manner as it is through the ports 13 and 14 when the latter are closed.

20 To actuate the valves the levers 19 and 20 are jointed respectively to the push rods 23 and 24, the latter being connected at their lower ends to the cam rolls 25 and 26 which bear respectively against the actuating cams 27 and 28 on the cam shafts 29 and 30. These cam shafts are driven through gears 31 and 32, meshing with the pinion 33 on the crank shaft, at one-half the speed of the crank shaft. Each cam is provided with a raised portion which, when brought beneath the cam roll, lifts the push rod and causes its respective valve to retract into the annular space and open its respective port. The pressure of the valve-closing spring is relied upon to close the valve when the raised portion of the cam has passed beyond the cam roll. Such opening movement takes place once for each two double strokes of the piston.

40 It will be observed that the spring is effective for positively closing and maintaining the valve closed during compression and firing, while the cam is utilized for opening the valve at the appropriate time. In 45 the illustrated form of engine the spring pressure is provided by the main springs 34 and 35, which encircle the push rods 23 and 24, respectively, and press the cam rolls down against the edges of the cams 27 and 50 28. The push rods and associated parts are housed in by the protecting casings 36 and 37. To supplement the pressure of the springs 34 and 35, as well as to take up lost motion in the actuating connections of the 55 valves, auxiliary springs 38 and 39 are utilized to assist in closing the valves. These springs are seated exteriorly the cylinder head 8, being protected by the caps 40 and 41. Each spring is under compression and 60 pressed down against a collar 42 carried by the plunger rod 43, the latter passing through the flange of the cylinder head and having its opposite end seated upon one of 65 the lugs 22. When the lift of the cam passes beyond the cam roll the auxiliary spring

adds its pressure to that of the spring 34 and assists in depressing the valve to a closed position.

It will be seen that the slide valves being separated segments tend to expand or press outwardly under the pressure of the explosion chamber. This causes the valves automatically to seat, their resistance to leakage being thereby automatically increased as the pressure of compression or during the working stroke increases. I have found that this pressure is ample to seat the valves and prevent all leakage with a very small area of the valve exposed, and that if too great an area be exposed to the pressure of the explosion chamber trouble may be experienced in moving the valves. In the present form of engine the valves are required to be moved under pressure only near the end of the working stroke, when the pressure is relatively low. To reduce the working pressure against the valves I have, however, arranged them so that preferably an intense pressure is only applied to a relatively small area of the valve, and herein only to that portion of the slide which is required for closing its port and which projects below the end of the cylinder head. To this end the segments are formed in less than half sleeves, so that their longitudinal edges are separated and do not 95 meet. The two diametrically opposite spaces between the cylinder head and the cylinder, and intervening between the adjacent edges of the sleeves, are filled by a separating member 44 (see Fig. 3), which is pinned or otherwise secured to the walls of the cylinder head and entirely fills the space between the cylinder head and the cylinder. Each slide valve slides in what is in effect a guide way, having an arc-shaped formation, its edges 100 having a sliding fit against the edges of the separator 44.

To assist in seating the slides, rings 45, 46 are employed at the upper and lower ends of the projecting portion of the cylinder 110 head, such rings engaging each slide and extending around the entire circumference of the cylinder head. If desired such rings may constitute packing rings, but the slides preferably have a close fit in the annular space between the head and the cylinder, and no additional packing may be required, the principal object being to prevent the access to the inner side of the slides of intensely high pressure fluid, or the accumulation of 115 pressure fluid thereat which will tend to create too high a friction between the valve and the cylinder walls against which it seats.

The inner face of the valve is preferably formed of uniform dimensions so that it 125 closely fits the cylinder walls and provides no pockets or spaces for the accumulation of pressure fluid.

It may be desirable to increase slightly the pressure against the inner faces of the slides 130

and to that end I have herein shown shallow chambers 47 and 48 extending part way around the walls of the head. The inner faces of the slides are exposed to these chambers and leakage conduits 48 and 49 can be provided to conduct pressure fluid from the explosion chamber to these chambers. These chambers may be made as large or small as required to insure the necessary seating of the valves, or they may be entirely omitted.

In Fig. 5 the piston is shown during its admission or suction stroke, the admission valve 15 having been retracted into the annular space and having opened the admission port 13 to the cylinder. The exhaust valve has been previously closed and is still maintained closed by its spring 39.

The conditions which pertain during the compression stroke are represented in Fig. 6. The piston is here shown as having started on the compression stroke, the admission valve 15 having been previously closed by its spring 38, and the exhaust valve being still maintained closed by its cam 28. Under these conditions the increasing compression within the cylinder increasingly presses the valves against their respective seats, so that as the compression increases so also does the resistance to leakage at and about the valves.

In Fig. 7 the conditions at the commencement of the working stroke are represented, the piston having started on its second forward movement and both the valves being still maintained closed by their respective springs.

In Fig. 8 the piston is shown as having completed its working stroke and as starting on the return or exhaust stroke, the exhaust valve 16 having been caused to open by its cam at the commencement of the exhaust stroke.

In Fig. 4 I have shown a modified form of the engine shown in Fig. 1, the separator 44 being omitted so that there is left a space 50 between the edges of the slides, through which space pressure fluid can pass freely to the upper end of the annular space 50. This results in balancing the pressure on opposite ends of the slide, while the access of intense pressure to the inner face of the slide is prevented by the spring ring segments 51 and 52, which bear against each slide at the top and bottom, extending circumferentially for substantially the full extent of the slide.

The valves may be given a very short stroke, herein the equivalent only of the port opening plus the necessary lap, and through the use of the cams as actuating agents may be moved each at such an appropriate time as gives the most effectively timed port opening for admission and exhaust. Thus, during suction stroke, the admission valve

can be opened almost instantly after the commencement of the admission stroke and remain open until a little after the completion of the stroke. On the other hand, the exhaust valve may be opened near the very close of the working stroke and can be kept open until the completion of the exhaust stroke of the piston. By modifying the shape of the cams the precise timing of the valves can be independently varied as may be desired and preferably I so set the cams that the exhaust valve is not closed until a few degrees after the completion of the exhaust stroke of the piston and not until the admission valve has started to open, so that there is a slight interval during which both valves are opened permitting a momentary scavenging action.

The opening and closing movements of the valves in each case are effected very rapidly by means of the cams. This adds materially to the effectiveness of the admission, compression, working, and exhaust strokes.

The cam-operated movement of the valves and the short travel required produces a minimum of wear. It will be observed moreover that the valves are only in motion when the internal pressure is slight, periods of compression and firing occurring when the valves are stationary. This not only reduces the frictional wear of the valves but also the power required to move them and provides conditions which assist in preventing leakage.

The valves as herein shown are preferably located at the rear of the working space of the cylinder and out of contact with the piston, this placing them out of the direct path of heat conduction or dispersion which takes place from the working cylinder space through the cylinder walls to the water jacket. The slide valves therefore are not only themselves out of the direct path of heat which must be dissipated through the cylinder walls and that intense heat which tends to interfere with their effective operation is avoided, but the cooling of the cylinder is much more effectively carried out where the heat does not have to traverse the valves themselves interposed between the piston and the cylinder walls.

It will be observed that with the valves located having the major portion of each within the annular space between the cylinder head and the cylinder they are not only protected against the access of pressure to their inner faces but are shielded by the projecting cylinder head from the intense heat of the combustion chamber during the working stroke, the only portions of the valves which are thus exposed being the short projecting ends which cover the ports.

While the valves might be arranged upon seats not constituting a part of the cylinder bore, preferably as herein shown they are

seated in a continuation of the cylinder bore, being however in a non-concentric or non-overlapping relation to the piston.

It will be understood that the terms "front", "rear", "top" and "bottom" as applied to the engine and its cylinder are merely terms of description applied to the specific drawings herein annexed to facilitate a more ready understanding of them, and have no significance as applied to the generic principles of my invention, various embodiments of which may be made wherein the relation of the parts thus referred to may be reversed or variously altered.

15 While I have herein shown and described for purposes of illustration one specific form of the invention, it is to be understood that the latter is not limited to the precise construction of features disclosed nor to the 20 form or relative arrangements of parts nor to the particular type of engine described, but that extensive modifications may be made in the illustrated embodiment of the invention without departing from the spirit 25 thereof.

I claim:

1. An internal combustion engine comprising a cylinder, a piston, a cylinder head extending into the cylinder but terminating 30 short of the rearward movement of piston travel, admission and exhaust ports, a pair of arc-shaped slide valves adapted to open and close said ports, said valves working in an annular space between the cylinder head 35 and the cylinder and having edges out of contact, said valves being also located beyond the rearward limit of the piston travel, operating means for the valves extending to the said rearwardly located portion thereof 40 and located outside of the cylinder, and means for preventing the access of an intense seating pressure to the inner faces of said valve.

2. In an internal combustion engine the 45 combination of a cylinder, a piston, a cylinder head extending into the cylinder but terminating short of the rearward limit of piston travel, admission and exhaust ports, arc-shaped segmental slide valves for controlling said ports, said valves being seated against the cylinder walls and having their edges out of contact and located beyond the rearward movement of piston travel, operating 50 means for the valves extending to the

said rearwardly located portion thereof and 55 located outside of the cylinder, and a separating member filling the spaces between the separated edges of the valves.

3. In an internal combustion engine the combination with a cylinder, a piston, admission and exhaust ports, a cylinder head having an inwardly projecting portion terminating short of the rearward limit of piston travel, independent separated segmental slide valves working between the cylinder 65 head and the cylinder and adapted to control said ports, said valves being located beyond the rearward limit of piston travel, operating means for the valves extending to the said rearwardly located portion thereof 70 and located outside of the cylinder, and packing ring segments in said head adapted to prevent the access of intense pressure to the inner faces of the valves.

4. An internal combustion engine having 75 a cylinder, a piston, cylinder ports, an internally projecting cylinder head terminating short of the rearward movement of piston travel, and operating means for the valves extending to the said rearwardly located portion thereof and located outside of the cylinder, and segmental arc-shaped slide valves 80 presenting each a substantially smooth face in sliding contact with said head and adapted to be projected beyond the same to close 85 each its respective port, said slides having their edges out of contact and being located beyond the rearward movement of piston travel.

5. In an internal combustion engine the 90 combination of a cylinder, a port, a piston, a segmental slide valve controlling said port, a cylinder head having a portion projecting within the cylinder to cover the major part 95 of said valve and protect the same from intense pressure, and a pressure chamber formed in the inner face of said head and communicating with the explosion chamber of the engine, said valve being exposed to said chamber.

In testimony whereof, I have signed my name to this specification, in the presence of two subscribing witnesses.

ADOLPH ROSNER.
